UNITED STATES PATENT OFFICE.

GEORGE W. COOKE, OF JAMAICA, NEW YORK, ASSIGNOR TO GEORGE W. COOKE CO. INC.,
A CORPORATION OF NEW YORK.

FAUCET.

Application filed April 19, 1924. Serial No. 707,588.

To all whom it may concern:

Be it known that I, GEORGE W. COOKE, a citizen of the United States, residing at Hillcrest, Jamaica, in the county of Queens 5 and State of New York, have invented certain new and useful Improvements in Faucets, of which the following is a full, clear, and exact description.

When liquids, such as lubricating oil, are 10 shipped in barrels or drums or other containers from which the liquid is to be dispensed by the purchaser, it is impractical to provide the containers prior to shipment with the ordinary faucet or other valve 15 devices for drawing off the liquid because of the likelihood of injury to such projecting devices in transit. The removal of the bung or other stopper from the container and properly fitting a draw-off valve in the 20 bung opening is inconvenient and oftentimes the occasion of considerable difficulty. The desirability of originally equipping the containers with suitable faucets is manifest, and various expedients 25 for meeting this situation have been proposed, most commonly the employment of a reversible valve or faucet which in one position serves as a stopper or bung projecting only slightly or not at all beyond the 30 wall of the container, and in the reversed position becomes a projecting draw-off member.

I have devised a construction for this purpose which obviates the reversal of the faucet, and which, while of quite general utility, is well adapted for the heavy steel drums or 35 barrels commonly used for containing oils. In accordance with my invention the outer end of the faucet becomes the bung or stopper and my invention is therefore well adapted to faucets of the screw plug type, since I can provide the end of the screw plug with a flat head which may bear against the wall of the container in the sealed position, preferably with an interposed gasket. The inner end of the faucet is also provided 45 with a flange which may bear against the inner face of the wall, also with an interposed gasket.

With this construction, it is only necessary 50 to move the faucet into the container until the outer flange bears against the wall to use the faucet as a bung, and to fully withdraw it until the inner flange bears against 55 the wall to render the faucet available for

use. Suitable provision is made at each end of the faucet to cause it to fit tightly into the bung opening, such as screw threads, on the one end on an enlarged portion of the faucet body member immediately in front 60 of the flange, and on the other end on an enlarged neck of the plug if that type of faucet is employed.

Convenience in assembly requires that there be a separate, removable bung member 65 into which the faucet screws or otherwise fits, and my invention therefore also contemplates a suitable bushing, preferably internally and externally screw threaded, which removably screws into a spud or the 70 like integrally secured, as by welding, to the container wall about the bung opening. The bushing will have an outer flange which will bear against the outer face of the container wall through the medium of an interposed gasket.

My invention also includes other features and details of construction, as will herein-after more fully appear. I shall now describe the illustrated embodiment of my invention, and shall thereafter point out my invention in claims.

Fig. 1 is an elevation of an end portion of a drum or barrel with a portion of the head in section and showing in elevation a faucet 85 construction embodying my invention in sealing or shipping position;

Fig. 2 is an enlarged longitudinal central section of the faucet and bushing and of the adjacent portion of the container, with the 90 faucet in the same position as in Figure 1;

Fig. 3 is a view similar to Figure 2 showing the faucet in dispensing position;

Fig. 4 is an outer end view of the faucet;

Fig. 5 is a transverse section on line 5—5 95 of Figure 3.

The faucet device is shown as applied to the head or crown 1 of a barrel or drum 2. A collar or spud 3 is welded to the inner face of the head around the bung opening, 100 and this spud is provided with internal screw threads. Screwing into this spud is a flanged bushing 4 having both internal and external screw threads. This bushing serves as a removable bung member and in assembly is screwed down tightly with the flange bearing against the outer face of the head through the medium of an interposed gasket 5.

The faucet has a tubular body member 6 110

which is of a smaller diameter than the internal opening of the bung member 4, except at its rear end where it has a portion 6^a enlarged of the same diameter as the internal size of the bushing 4. This enlarged portion 6^a is provided with external screw threads adapted to engage with those in the bushing 4, and it terminates at its rear end in a circumferential flange 6^b. A washer 6^c 5 surrounds the portion 6^a immediately in front of the flange 6^b.

The body member 6 is provided intermediate of its ends with an internal circumferential valve seat 6^d, and the valve chamber 10 in advance thereof is internally screw threaded and has a lateral discharge opening 6^e. A valve plug 7 screws into this valve chamber and in the form shown, this valve plug is made hollow throughout its length 15 and has a wooden gasket 8 in its inner end adapted to seat against the valve seat 6^d when the screw plug is turned in and thus close the faucet.

Immediately back of the screw threaded 20 stem portion of the plug 7 which screws into the valve chamber, the plug is provided with an enlarged screw threaded neck portion 7^a of the same diameter as the enlarged portion 6^a of the body member. At its outer end the plug terminates in a circumferential flange 7^b, while a gasket 7^c surrounds the neck portion 7^a immediately in front of the flange 7^b. The outer end of the plug may be closed 25 by a sheet metal cap 9 on which may be imprinted any desired legend. The flange 7^b and also the flange of the bushing 4 are preferably hexagonal or of other non-circular shape to accommodate a wrench. Also the body member of the valve is provided 30 with a hexagonal portion immediately back of the valve chamber for the same purpose.

In assembling the parts, the faucet member with the plug removed is inserted into the bushing, so that the inner end of the bushing is toward the inner enlarged end 35 of the body member. The plug is then screwed into the valve chamber so as to sit tightly against the seat 6^d, and the neck portion 7^a of the plug is screwed into the bushing, which is the position of the parts shown 40 in Figures 1 and 2. The bushing is then screwed into the bung opening. The head of the plug then bears against the outer face 45 of the flange of the bushing with the gasket 7^c between the two faces. The length of the plug stem is such that in this position the valve is tightly closed, and an effective seal 50 is thus secured. This will be done after the container has been filled and while it is standing on end with the bung up. The chime of the barrel extends beyond the outer 55 face of the head of the plug in this position, and the barrel can, therefore, be turned safely to stand on either end during shipment. 60 When the barrel is delivered the purchaser 65

has only to unscrew the outer end of the faucet from its engagement with the bushing 4 and withdraw the faucet and screw its inner end 6^a into the bushing until the gasket 6^c is tightly compressed between the 70 flange 6^b and the inner end of the bushing. The barrel can then be turned on its side and the faucet used in the usual way for withdrawing the contents of the barrel.

It is obvious that various modifications 75 may be made in the construction shown in the drawings and above particularly described within the principle and scope of my invention.

I claim:

1. A combined faucet and stopper device 80 for containers, comprising, in combination with a removable tubular bung member for the container, a faucet having a body member of a size adapted to pass freely through 85 the bung member and having at its inner end an enlarged portion shaped to fit tightly in the bung member and terminating in a circumferential flange adapted to bear against the inner end of the bung member, 90 and a plug member for opening and closing the faucet fitting within the outer end of the body member and removable therefrom and having an enlarged portion beyond the 95 end of the body member shaped to fit tightly in the bung member and terminating in a circumferential flange adapted to bear against the outer face of the bung member.

2. A combined faucet and stopper device 100 for containers comprising, in combination with a removable internally screw threaded bung member for the container, a faucet having a body member of a size adapted to pass freely through the bung member and having at its inner end an enlarged screw 105 threaded portion adapted to screw into the bung member and terminating in a circumferential flange adapted to bear against the inner end of the bung member, and a plug member for opening and closing the faucet fitting within the outer end of the body member and removable therefrom and having an enlarged screw threaded portion beyond the end of the body member adapted 110 to screw into the bung member and terminating in a circumferential flange adapted to bear against the outer face of the bung member.

3. A combined faucet and stopper device 115 for containers comprising an internally and externally threaded bushing adapted to screw into a threaded opening in a container wall and serve as a bung member and having a circumferential flange at its outer 120 end to bear against the outer face of the container wall, a tubular faucet body member of a size to pass freely through the bushing and having an integral screw threaded 125 enlargement at its inner end adapted to screw into the bushing and terminating in 130

a circumferential flange adapted to bear against the inner end of the bushing and having a circumferential internal valve seat and a lateral outlet opening and internal 5 screw threads beyond the valve seat, and a screw plug for opening and closing the faucet engaging the screw threads within the body member and having an enlarged

screw threaded portion beyond the end of the body member adapted to screw into the 10 bung member and terminating in a circumferential flange adapted to bear against the outer face of the bushing.

In witness whereof, I hereunto subscribe my signature.

GEORGE W. COOKE.
